FIG.1

FIG.2

FIG.3

FIG. 1 is a front elevational view of a spoon showing my new design;

FIG. 2 is a side elevational view thereof; and
FIG. 3 is a back elevational view thereof.

The design is intended for use on sets comprising spoons, forks, knives and similar articles of flatware.

The essential feature of my design resides in the particular handle portion which is shaped as shown.

I claim:

The ornamental design for a spoon, as shown and described.
